UNITED STATES PATENT OFFICE.

MILTON WERTHEIMER, OF BALTIMORE, MARYLAND.

WRAPPED CIGAR.

1,128,828.

Specification of Letters Patent.

Patented Feb. 16, 1915.

Application filed April 18, 1913. Serial No. 762,100.

To all whom it may concern:

Be it known that I, MILTON WERTHEIMER, a citizen of the United States, residing at Baltimore, in the State of Maryland, have 5 invented certain new and useful Improvements in Wrapped Cigars, of which the following is a specification.

This invention relates to an improved paper wrapper as a covering for cigars.

10 The accompanying drawing illustrates the invention.

Figure 1 shows the shape of the wrapper or cover spread out flat, and a cigar placed thereon at the shorter edge ready to be covered by rolling. Fig. 2 shows the appearance of a cigar and its cover in the first stage when the cover has been rolled around the cigar. Fig. 3 shows the second stage in which both ends of the cover are twisted 20 and project straight away from the cigar ends. Fig. 4 is a view of a covered cigar finished.

In order to attain the desired object and produce the desired result the wrapper or 25 cover in the flat blank must have the particular outline shape shown in Fig. 1 of the drawing.

The wrapper may be made of any suitable material such as soft paper, or thin woven 30 fabric paraffined. The wrapper, A, in its flat condition and in its longer direction has two parallel side edges, b, c, of unequal length, and two end edges, d, both of which commence at the shorter longitudinal edge, b, and extend in oblique directions away 35 from each other and terminate at the longer longitudinal edge, c. By this construction two acute angle points, e, are both formed by the same longer edge, c, together with 40 the two oblique edges. The two angle points are the only parts of the wrapper that project beyond the ends of the cigar when the latter is completely enveloped. It will be seen the two angle points, e, are both at the 45 opposite extremities of the longer edge, c, and this location of the two extreme points makes it possible, when the wrapper has been rolled around the cigar as in Fig. 2, to twist said points in the same direction.

50 These wrappers may be applied to cigars by various proceedings; it may make the operation clearly understood therefore by stating that in practice it has been found preferable to apply these wrappers to cigars

by employing a machine designed for that 55 purpose.

In order to envelop a cigar, F, in this wrapper, according to my invention, the cigar should be placed on the flat wrapper along the shorter edge, b, as shown in Fig. 60 1, and then the cigar and wrapper both rolled toward the longer edge, c, as indicated by the dart, and by such rolling the cigar will be enveloped by its wrapper, A. The relative condition of the cigar and the 65 ends of the wrapper that project beyond the cigar ends at this stage, is shown in Fig. 2 of the drawing.

The rolling of the cigar and wrapper in the same direction should be continued at 70 this stage, and while rolling the operator will grasp the two projecting ends of the wrapper designated, g, with the fingers of both hands and hold said ends firmly while the wrapped cigar continues to revolve; the 75 effect of this action will be to twist both projecting ends in the same direction that the body has been rolled, and said twisted ends, h, are tapered as shown in Fig. 3. The wrapper at this stage will be snugly 80 fitted around the cigar.

The twisted part of the ends, h, seen in Fig. 3, may then be curled to form a small bunch, as at, i, in Fig. 4, and the free extremity, j, of said twisted end may lie exposed alongside of the said small bunch. No further disposition is made of this extremity. Neither a tie, nor adhesive matter 85 of any kind is used.

Cigars covered in this way are not only 90 kept clean but in good condition otherwise, by the wrapper. I have used these paper wrappers also on cigars that were first covered with tin foil, and then the paper wrapper of the shape herein shown put on over 95 the tin foil in the manner hereinbefore described. The claims hereinafter are intended to apply whether tin foil is used or not used.

When it is desired to remove from a cigar 100 a paper cover of the kind herein shown and described, a person may uncurl the bunch, i, at the ends and grasp the two twisted extremities and pull both in opposite directions at the same time; this pulling action 105 will cause the wrapped cigar to revolve automatically in the direction reverse to that of winding and in so doing the twisted ends

will unwind and the cover will at once loosen and separate from the cigar.

Having thus described my invention what I claim and desire to secure by Letters Patent is:—

- 5 1. A cigar package comprising a cigar and a wrapper therefor said wrapper having a longitudinal edge that is longer than and extends lengthwise of the cigar and opposite end-edges which extend in directions whereby the wrapper's length is diminished in a direction away from said longitudinal edge, said wrapper being wound about the cigar and the projecting opposite end portions of the wrapper being twisted in the same direction relative to the cigar, whereby upon pulling said twisted ends the wrapper will unwind to release the cigar.
- 10 2. A cigar package comprising a cigar and a wrapper having two side-edges one of which is longer than the other and also longer than the cigar, and two end-edges that extend from opposite ends respectively of the longer side edge to the corresponding opposite ends of the shorter side edge, said wrapper being wound about the cigar and
- 15
- 20
- 25

having the opposite projecting ends of the longer edge twisted in the same direction relative to the cigar whereby upon pulling said twisted ends the wrapper will unwind to release the cigar.

3. A cigar package comprising a cigar and a wrapper having a side-edge that is longer than the cigar and extending in a direction lengthwise of the cigar said wrapper also having end-edges that extend from opposite ends of the longer side-edge and in a converging direction whereby to gradually reduce the length of the wrapper,—the wrapper being wound about the cigar with the longer edge outermost and the projecting portions of the converging end-edges being twisted, the twists beginning at opposite ends of the outermost longer side-edge whereby to draw on said longer side-edge from opposite ends thereof.

In testimony whereof I affix my signature in presence of two witnesses.

MILTON WERTHEIMER.
